UNITED STATES PATENT OFFICE

2,590,498

CHECK WIRE TENSION MEASURING APPARATUS

Harry H. Bomberger, Hershey, Pa.

Application August 3, 1949, Serial No. 108,301

1 Claim. (Cl. 73—143)

1

This invention relates to a check-wire holder and has for its primary object to enable corn or similar row crops to be planted in even rows both longitudinally and transversely of the field.

Another object of this invention is to provide an efficient and easily adjustable holder for a check-wire for a corn planter, the holder retaining the check-wire in the same tensioned position for each row.

These and ancillary objects are attained by this invention, a preferred embodiment of which is set forth in the accompanying drawing, wherein:

Figure 1 is a view in perspective of a check-wire, illustrating the novel anchoring means therefor as taught by this invention;

Figure 2 is a longitudinal vertical sectional view of the holder;

Figure 3 is an enlarged transverse sectional view taken on line 3—3 of Figure 2;

Figure 4 is an enlarged transverse sectional view taken on line 4—4 of Figure 2; and

Figure 5 is a cross sectional view taken on line 5—5 of Figure 2 and being shown on an enlarged scale.

Referring now more particularly to the accompanying drawing, it is to be noted that the check-wire 10 is held under tension by holders 12, which are detachably hooked to the opposing ends of the wire and in turn anchored to stakes 14, which are driven into the ground. The stakes are provided at their upper ends with handles 16, which expedite the extraction of the stakes and also aid in the positioning of the stakes.

Attention is directed to Figures 2 and 5 for a more detailed explanation of the holders 12, which are identically constructed and employed. The holders comprise an elongated tubular member 18 which is formed with opposing externally threaded ends 20 and 22. A cap 24 is threaded on the end 20 and is formed with an enlarged head 26. A slot 28 is longitudinally formed in the member 18 adjacent the end 20 and a pin or set screw 30 is slidably disposed therein, the pin having its inner end adjustably secured in a disk 32.

The disk 32 is slidably disposed in the tubular member and is formed with a centrally disposed internally threaded bore 34, in which is secured the threaded end 36 of an elongated rod 38.

The rod is slidably disposed through the head of the cap 24 and terminates in an externally threaded end 40. A turnbuckle 42 connects the end 40 of the rod to an eye bolt or anchoring member 44, which is positioned on the stakes 14. The end 36 of the rod is formed with a flattened axially aligned apertured ear or extension 46 in which one end 48 of a spring 50 is anchored. The opposite end 52 of the spring is attached to a hook 54 having a claw end 56. The shank of the hook is suitably attached to the tube 18, as by being threaded onto a cup member 58, which in turn is threaded and locked on the end portion 22 of the member 18 as illustrated in

2

Figure 2. The claw end 56 of the hook engages one end of the check-wire 10.

Means is provided for locking the rod 38 against sliding movement in the tube and includes a locking rod or pin 60, which is formed with an externally threaded end 62 disposed radially through the head 26 of the cap 24 and is adapted to frictionally bear against the flattened side 64 of the rod.

10 A knurled angular extension 66 is formed on the end 62, whereby the end may be rotated into a locking or unlocking position.

With respect to Figures 1 and 2, it can be seen that the check-wire is stretched across the field and the opposing ends are held by the hook members 54.

15 The pin 30 functions as an indicator to register the tension and, accordingly, the outer surface of the tube 18 is calibrated adjacent to and 20 parallel with the slot 28.

In use of the device, after adjusting the tension in the check-wire 10 to the degree desired, and locking the rod 38 against movement relative to the tube 18, as by tightening down the 25 locking member 60, the position of the indicator 30 on the calibrated section of the tube 18 is noted. Thereafter, by utilizing a like procedure to apply the same tension in succeeding wire as the planting proceeds, a uniform spacing of 30 the plantings throughout the field may be obtained.

Having described the invention, what is claimed as new is:

In a wire tension checking device, an elongated tube, apertured cap members threaded onto the ends of said tube, a rod slidably extending through the aperture in one of said cap members, resilient means in said tube and attached to the inner end of said rod, said rod 35 having a flattened portion, a threaded pin arranged in the flange of the last-mentioned cap member and engageable with said flattened portion for locking said rod, means on the outer end of said rod for fastening same to an anchor 40 member, a hook member having a shank passing through the aperture of the other cap member and threaded engaged therein, the free end of said shank being secured to the opposite end of said resilient means and means for indicating 45 the extent of movement of said rod relative to said tube.
